Term of patent 14 years

(Cl. D9—2)

FIG. 1

FIG. 2

FIG. 3

FIGURE 1 is a perspective view of a pet clean-up rake showing my new design;

FIGURE 2 is a side elevational view of my pet clean-up rake;

FIGURE 3 is a side elevational view corresponding to FIGURE 2 but showing only the lower portion of the rake and the view being on a larger scale than that utilized in FIGURE 2;

FIGURE 4 is a front elevational view of my rake, the handle having been removed for space reasons;

FIGURE 5 is a top plan view of my rake with the handle removed;

FIGURE 6 is a bottom plan view of my rake with the handle again being removed for drafting simplicity, and

FIGURE 7 is a rear elevational view of my rake, the handle again being removed for drafting reasons.

I claim:

The ornamental design for a pet clean-up rake, as shown.
